UNITED STATES PATENT OFFICE.

WINFIELD P. PEMBROKE, OF ROCHESTER, NEW YORK.

CARBURETOR.

Application filed March 2, 1915. Serial No. 11,571.

To all whom it may concern:

Be it known that I, WINFIELD P. PEMBROKE, of Rochester, in the county of Monroe and State of New York, have invented certain new and useful Improvements in Carburetors; and I do hereby declare the following to be a full, clear, and exact descriptions of the same, reference being had to the accompanying drawings, forming a part of this specification, and to the reference numerals marked thereon.

My present invention has for its object to provide a carburetor for vaporizing liquid fuel for use in explosive engines in which two different sources of supply of fuel are provided, one for furnishing the rich mixture required for low speed operations of the engine, or when the engine is being first started, and the other for furnishing the leaner carbureted mixture used for higher speeds, the parts of the carburetor being so arranged that the operation of these two instrumentalities is automatic and is governed by the demands created by the engine, under varying conditions of the load applied to the engine. To these and other ends the invention consists in certain improvements and combinations of parts, all as will be herein-after more fully described, the novel features being pointed out in the claims at the end of the specification.

In the drawings:

Figure 1 is a side elevation of a carburetor showing one embodiment of my present invention;

Figure 2 is a top plan view thereof;

Figure 3 is a vertical central sectional view, and

Figure 4 is a detail sectional view taken on the line 4^x-4^x of Figure 1.

Similar reference numerals throughout the several views indicate the same parts.

My present invention provides a carburetor having a dual source of fuel supply whereby the greatest efficiency can be developed in an explosive engine, one of the sources intended particularly to supply the required amount of liquid fuel to produce the rich mixture required when the engine is working at low speed, as occurs when the cranking operation is performed to start it, or when the engine is endeavoring to develop its maximum power at a low number of revolutions, while the second source of fuel supply, which operates conjointly with the one first mentioned furnishes the fuel which is

to be mixed with the greater volume of air drawn through the carburetor when the pistons of the engine are reciprocated with greater rapidity. With this last mentioned means of supplying the liquid fuel automatic valves are employed which are operated by the inrushing air to control the admittance of air in the required quantities to form a proper carbureted mixture.

In carrying out my invention I provide a carbureting chamber having a receptacle for liquid fuel, such as gasoline, the quantity of which admitted to the receptacle is proportioned to the requirements of the particular engine with which the carburetor is to be used. Means are also provided in the chamber whereby the volume of the air currents traversing the chamber is caused to pass into intimate contact with the surface of the fuel held in the receptacle, or if needs be, to pass through the body of fluid to the end that the air may become saturated and a very rich explosive mixture created. The arrangement of the fluid inlet by which the liquid fuel is supplied to the receptacle is so arranged that after the latter has been emptied and the very rich carbureted mixture, provided at the outset for the starting of the engine, is exhausted the receptacle will not be again filled while the engine is in operation, the fluid which passes into the chamber being evaporated and utilized at low engine speed operation before it gravitates into the receptacle.

In illustrating one embodiment of my present invention I have shown a carburetor comprising a hollow casing forming a mixing chamber A and a float chamber B, which are arranged side by side, the former having the primary air inlet 1 and the outlet 2 controlled by the usual throttle 3 which is opened and closed by the lever 4. The air inlet 1 is arranged somewhat above the lower end or bottom of the chamber A and within the latter is a transverse wall or partition 5 which directs the incoming currents of air downwardly, the lower end of the wall being arranged in proximity to the bottom of the chamber which forms the receptacle for the liquid fuel. This receptacle is preferably formed by a plug 6 which is screwed into the lower end of the chamber A and may be provided with a shallow depression or recess 6^a. Extending through the part 6 is a tubular screw 7 which is adjustable from the exterior of the carburetor and constitutes an

overflow or stand pipe for controlling the level which the body of liquid fuel in the bottom of the chamber A may assume. Also arranged in the chamber A and cooperating with the receptacle is an adjustable air valve 8, which is semi-cylindrical in cross section and forms a movable lower end on the partition 5 which can be adjusted to determine the thickness of the air sheet passing beneath the partition, the proximity which the volume or main portion of air currents assume to the surface of the liquid contained in the bottom of the mixing chamber, or to cause said air to pass through the body of the liquid fuel until this is completely evaporated. The adjustment of the valve or gate 8 depends principally upon the gravity of the fuel and the condition of the atmosphere at different times. Other forms of valves may be used in lieu of the valve or gate 8, or other expedients adopted to control the thickness of the air sheet, for instance the plug 6 may be rotated and thus raised or lowered relatively to the lower end of the partition 5. The air valve 8 cooperating with the fluid receptacle extends transversely of the mixing chamber and is journaled in the side walls thereof and exteriorly of the chamber at one of its ends it is provided with a head 8^a having a transverse arm or handle 19.

The fuel is admitted into the mixing chamber from the float chamber B through the nozzle or orifice 9, the area thereof being controlled by a needle valve 10 which is adjusted by a thumb nut 11 on the threaded outer extremity of the valve stem 12. The latter is guided to move longitudinally in apertures in the wall of the casing, the partition 5 and the exteriorly arranged bracket 13 and it is held yieldingly in its innermost adjusted position by means of a coil spring 14 so that the needle valve may be retracted to allow the orifice 9 to be opened to permit the unrestricted flow of the liquid from the chamber B into the chamber A. This adjustment of the needle valve may be accomplished in any suitable manner, the means shown consisting of a cam 15 journaled on a pivot 16 carried on the sleeve 17 and rigidly connected to the valve stem 12, the cam being moved by a pull rod 18 or other suitable device, and bearing against the side wall of the casing will move the stem longitudinally in an outward direction.

At the side of the chamber A is a tubular extension A' normally closed at its inner end by a valve head 24 and having at each side apertures 25, the area of which may be adjusted by a collar 26 which is locked in the adjusted position by a screw 27. These parts constitute an auxiliary air inlet through which the required volume of air may be admitted to furnish the carbureted mixture required for intermediate engine speeds. At

cranking speed the carbureted mixture is formed by the intimate association of the air with the deposited liquid fuel at the bottom of the chamber A. At low engine speed, up to a predetermined number of revolutions, 70 the mixture is formed by the air entering the inlet 1 and commingling with the fuel sprayed from the main nozzle 9. As the demands of the engine increase the suction of air in the chamber A increases the quantity 75 of fuel supplied, up to a given point, which is sufficient to carburet the additional supply of air which may be admitted through the auxiliary air inlet and when the limit of the capacity of this is reached further carburation is supplied for the maximum capacity 80 of the engine by bringing into play an additional fuel nozzle and air inlet.

The fuel supplied for the higher speed operations of an engine is obtained through 85 a jet or nozzle 28, the lower open end 29 of which is located in the float chamber B below the orifice 9, while its upper end leads into the auxiliary air inlet A', the latter being preferably located over the float 90 chamber to permit this simple arrangement of the parts. The flow of the fluid through the nozzle 28 may be controlled by the needle valve formed at the inner end of the screw threaded adjustable stem 28^a projecting upwardly through the bottom of the float chamber in alignment with the seat 28^b. The outer end of the auxiliary air inlet A' is normally closed by an apertured face plate a, against which rests a secondary 100 valve head 29^a. Both valve heads 24 and 29^a are slidably supported on a rod 30 and are held against their respective seats by coil springs 30^a and 31. A given quantity of air is admitted into the inlet A' through the 105 apertures 25. It will be seen from this arrangement of the parts that when the partial vacuum produced by the reciprocations of the pistons of the engine, becomes sufficient to overcome the tension of the spring 110 20^a that the valve 24 will be drawn inwardly to admit the amount of air required to supply the increased demands of the engine up to the full capabilities of the nozzle 115 9 to effect carburation. Further increasing demands of the engine upon the carburetor are met by the opening of the valve 29^a which uncovers the aperture in the face plate a and the adjustment of the parts is such that at this instant the suction created 120 causes the aspiration of fuel from the nozzle 28. The opening movement of the valves 24 and 29^a may be regulated to a nicety by adjusting the tension of the spring 30^a and the means which I have shown for accomplishing this is the providing of the stem 30 with a screw thread whereby it may be adjusted longitudinally to vary the distance 125 between the valve head 24 and the shoulder on the stem 30, against which the outer 130

end of the spring engages. Independent adjustment of the spring 31 is not required as it is customary to use a light spring, the tension of which is reduced when the valve 5 head 24 is retracted, the reduction of the tension depending also upon the distance the valve head 24 is moved inwardly.

The arrangement of the parts as shown is more than the combining of two carburetors 10 because in addition to bringing these parts together I have so arranged them with the two air valves and the air inlet that I have provided in the secondary carburetor means whereby it is possible to govern to a nicety 15 the time, or instant, according to the demands of an engine, at which the supply of auxiliary air for the primary fuel nozzle and the quantity of such air shall be admitted; and further, a point which is of 20 greater importance, I am able to govern the exact instant, during the period of speed increase of the engine, at which the discharge of fuel from the secondary nozzle shall begin. In other words, the arrangement 25 of the two valve heads in the lateral passage A' with an air inlet 25, of adjustable area, enables the fuel supply from the nozzle 28 to be checked while the necessary volume of air to satisfy the increased flow 30 of fuel from the primary nozzle 9 is allowed to pass through the opening controlled by the valve 24. It is understood, of course, that there is quite a range of speeds at 35 which an engine can be operated on the mixture supplied by the nozzle 9, the main air inlet 1 and the auxiliary air inlet comprising the apertures 25 and the opening controlled by the valve 24, but when the maximum speed is reached that can be maintained 40 by this source of supply it is highly important that the secondary fuel nozzle should begin to supply fuel and that still further quantities of air be then allowed to flow into the mixing chamber in exact proportion to the additional fuel supply. 45

The arrangement of the mechanism of the float chamber, by which the level of the liquid therein is controlled, may be of any desired construction, and for the purpose 50 of illustration I have shown the float b carried on the valve stem b' which opens and closes the inlet passage 32. In order to trip the float to perform the priming operation, so that the level of the liquid fuel 55 may rise to such a height that it will flow through the orifice 9, I provide in the top of the float chamber a spring retracted pin 33 which may be depressed by a bell crank lever 34, tripped by a cord or cable 35 leading preferably to a central point of control 60 from which the similar cord 18 is operated.

It will be noted that the springs 30^a and 31 are of such relative strength that the 65 spring 30^a will permit the operation of the

valve 24 independently of the operation of the valve 29^a. If, however, the reduction of the air pressure in the auxiliary mixing chamber A' is sufficient when the valve 24 is open the valve 29^a will also be actuated. 70 The operation of the valve 24 reduces the tension of the spring 31 on the valve 29^a permitting the operation of the latter valve only when the valve 24 is open.

It will also be noted that the nozzle 9 is 75 some distance above the bottom of the float chamber and the passage leading to the nozzle 28 is also some distance above the bottom of said chamber. In order to prevent air being admitted to said nozzles a partition b² is provided in the float chamber extending from a point near the bottom thereof to the top and enclosing the fuel passages 9 and 29. The partition extends below the normal surface of the fuel in the chamber B 80 and hence prevents admission of air in the chamber to the fuel passages 9 and 29.

The nozzle 9 is located just above the normal level of the liquid in the float chamber. When it is desired to accomplish a 90 priming operation the float is depressed by the means described, thus raising the liquid level above nozzle 9, so that the liquid flows through and into the depression 6^a. When the engine to which the carburetor is attached is running, and a decrease in pressure thus produced in chamber A, the liquid level in the compartment formed by the wall b² is raised by such decreased pressure transmitted through the nozzle. Therefore, the 100 liquid level is raised sufficiently to supply fuel through this nozzle when the engine is in operation, and such fuel is, of course, taken up by the incoming air, vaporized and supplied to the engine. Liquid fuel may 105 thus be caused to flow through the nozzle temporarily during the priming operation and to flow through the nozzle continuously during operation, but at all other times the liquid is below nozzle 9 so that no fuel is 110 wasted.

At low engine speeds valve 24 remains closed. At increased speeds, however, valve 24 is opened automatically by the reduced pressure in the primary chamber A to admit 115 to the latter air supplied through the openings 25 of the secondary chamber. At this point, of course, valve 29^a is closed and the reduction of pressure in the secondary chamber A is not sufficient to draw the fuel 120 through nozzle 28, so that the latter is not in operation. Air inlets 25 are manually adjusted to such a constant operating size of opening that the pressure in the secondary chamber A' falls at that higher speed of the 125 engine, or in other words at that reduced pressure in primary chamber A at which it is desired to bring the nozzle 28 into operation. In other words the openings 25 are so adjusted as to be insufficient in size to supply 130

the increased volume of air drawn past the open valve 24 by the reduced pressure in primary chamber A, and at this point fuel is drawn through nozzle 28. Valve 29^a is controlled by the adjustment of spring 30^a, as described, to open at the same reduced pressure in the secondary chamber at which liquid is drawn through nozzle 28, and, of course, valve 29^a is opened wider at still higher speeds to supply additional air for the additional fuel drawn through nozzle 28. It is to be noted that air is always passing through the secondary chamber before nozzle 28 comes into operation.

Liquid accumulates in the depression 6^a only when the float is depressed to permit a flow of fuel from orifice 9 to the depression 6^a for the purpose of priming the engine. At other times when the engine is operating any fuel flowing through the orifice 9 will be taken up by the ingoing air stream and no accumulation of fuel in the depression 6^a will occur.

I claim as my invention:

1. In a carburetor, the combination of a mixing chamber having an air inlet passage and a fuel inlet, an auxiliary air inlet passage communicating therewith and having an air inlet opening at its outer end, an inwardly opening valve for closing the opening between said auxiliary air inlet and the mixing chamber, a second valve normally closing the air inlet at the outer end of said passage, a spring normally closing said first valve, a second spring controlled by the first spring and operating to close the second valve, and an auxiliary fuel nozzle opening into the passage between said valves.

2. In a carburetor, the combination with a casing having communicating primary and secondary mixing chambers, the latter comprising an air inlet of fixed area and a normally closed inlet, of means for supplying fuel to each of the two chambers, a valve controlling the normally closed inlet, and a valve opening and closing automatically separating the two chambers and which is operated by differences in pressure in the

latter first to admit a given volume of air into the primary chamber from the inlet of fixed area and second, to cooperate with the first mentioned valve and said inlet to control the degree of the reduction of pressure produced in the secondary chamber relative to that produced in the primary chamber.

3. In a device of the character described, the combination of a casing having a primary mixing chamber, air supply means and fuel supply means therefor, a secondary mixing chamber connected by a passage with the primary chamber, a valve for said passage operated automatically by differences in pressure between said primary and secondary chambers, a fuel supply means for the secondary chamber, air supply means for said secondary chamber provided with means for adjusting the same to different constant sizes to produce the pressure in the secondary chamber required to operate said fuel supply means thereof at a predetermined pressure in said primary chamber, and automatic air supply means for supplying additional air to the secondary chamber during the operation of said fuel supply means thereof.

4. In a device of the character described, the combination of a casing having a primary mixing chamber, air supply means and fuel supply means therefor, a secondary mixing chamber connected by a passage with the primary chamber, a fuel supply means for the secondary chamber, an automatic pressure operated valve controlling said connecting passage, air inlet means affording a continuous supply of air to said secondary chamber, and manually operable means for adjusting said inlet means to different constant sizes unaffected by pressure to produce in the secondary chamber the pressure required to operate said fuel supply means thereof at a predetermined pressure in said primary chamber.
